[57] CLAIM

The ornamental design for a closure for a bottle or similar article.

DESCRIPTION

FIG. 1 is a perspective view of a closure for a bottle or similar article showing my new design, the bottle shown in broken lines for illustrative purposes only;

FIG. 2 is a top plan view thereof;

FIG. 3 is a front elevational view thereof; and

FIG. 4 is a side elevational view thereof, taken in the direction of the arrows along line 4—4 of FIG. 2.
